BOTTLE

Daniel Goldstein, New York, N. Y., assignor to
Schenley Industries, Inc., New York, N. Y., a
corporation of Delaware

Application April 10, 1951, Serial No. 14,786

Term of patent 14 years

(Cl. D58—8)

To all whom it may concern:

Be it known that I, Daniel Goldstein, a citizen of the United States of America, residing at city, county and State of New York, have invented a new, original, and ornamental Design for a Bottle, of which the following is a specification, reference being had to the accompanying drawing, forming a part thereof:

Figure 1 is a front elevation of a bottle, embodying my new design;

Figure 2 is a side elevation thereof;

Figure 3 is an opposite side elevation of the same; and

Figure 4 is a transverse section view therethrough, as seen on the line 4—4 of Figure 1.

I claim:

The ornamental design for a bottle, as shown.

DANIEL GOLDSTEIN.
